The ornamental design for a trim board as shown and described.

DESCRIPTION

FIG. 1 is a perspective view of a trim board showing our new design.

FIG. 2 is a front view of the trim board.

FIG. 3 is a back view of the trim board.

FIG. 4 is a right side view of the trim board.

FIG. 5 is a left side view of the trim board.

FIG. 6 is a top view of the trim board; and,

FIG. 7 is a bottom view of the trim board.

The broken lines in the Figures show portions of the trim board that form no part of the claimed design. The dot-dash lines represent the bounds of the claimed design.

The shade lines in the Figures show contour and do not claim surface ornamentation or treatment.
